(57) **CLAIM**

The ornamental design for an automobile fog light, as shown and described.

DESCRIPTION

FIG. 1 is a perspective view of an automobile fog light.

FIG. 2 is a front view thereof;

FIG. 3 is a side view thereof; and,

FIG. 4 is a top view thereof.

The drawings and descriptions represent the first left side embodiment. A second embodiment is the mirror image of the first embodiment. The broken lines are included for environmental purposes and form no part of the claimed design.

1 Claim, 4 Drawing Sheets

FIG. 1

FIG. 2

FIG. 3

FIG. 4
